US00D948033S

(12) United States Design Patent (10) Patent No.: US D948,033 S
Fang (45) Date of Patent: * Apr. 5, 2022

(54) ORAL IRRIGATOR

(71) Applicant: SHENZHEN FORTUNECOME TECHNOLOGY CO., LTD., Shenzhen (CN)

(72) Inventor: Xiaolin Fang, Shenzhen (CN)

(73) Assignee: SHENZHEN FORTUNECOME TECHNOLOGY CO., LTD., Shenzhen (CN)

() Term: 15 Years

(21) Appl. No.: 29/740,843

(22) Filed: Jul. 7, 2020

(30) Foreign Application Priority Data

Feb. 27, 2020 (CN) 202030062490.4

(51) LOC (13) Cl. 28-03

(52) U.S. Cl.

USPC D24/111

(58) Field of Classification Search

USPC D24/108, 111-115, 152, 176; D4/100-102, 110, 111, 138

CPC A61C 17/0202; A61C 17/028; A61C 17/0205; A61C 1/0092; A61C 17/02

(57) CLAIM

The ornamental design for an oral irrigator, as shown and described.

DESCRIPTION

FIG. 1 is a perspective view of an oral irrigator showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The broken lines in the drawings depict portions of the oral irrigator that form no part of the claimed design.

1 Claim, 9 Drawing Sheets
